UNITED STATES PATENT OFFICE.

OTTO RICKMEYER, OF MILWAUKEE, WISCONSIN.

SPARK-PLUG.

1,195,089.

Specification of Letters Patent. Patented Aug. 15, 1916.

Application filed December 1, 1915. Serial No. 64,511.

To all whom it may concern:

Be it known that I, OTTO RICKMEYER, a subject of the Emperor of Germany, residing at Milwaukee, in the county of Milwaukee and State of Wisconsin, have invented 5 new and useful Improvements in Spark-Plugs, of which the following is a specification.

This invention relates to improvements in 10 spark plugs and has particular application to a self-cleaning spark plug.

My present invention is in the nature of an improvement upon the device disclosed in my prior Patent No. 1,132,385, issued 15 March 16, 1915. My prior patent discloses a cleaner mounted upon each electrode of the spark plug in a manner to move thereon so as to remove carbon and other matter that may tend to deposit upon the electrode and 20 interfere with the operation of the spark plug, from the terminals of the plug. In my present invention, these cleaners are formed without waste of material and are so constructed that, in the operation thereof, 25 short circuiting of the spark plug is avoided. Furthermore, in my present invention, I employ means for positively restoring the cleaning devices to normal position succeeding the sliding thereof under the action of 30 the gases during the operation of the engine, thereby preventing sticking of the cleaners in the continued use of the plug.

My invention consists in the construction, combination and arrangement of parts hereinafter set forth in and falling within the 35 scope of the claim.

In the accompanying drawing; Figure 1 is a view in side elevation of a spark plug provided with cleaners constructed in accordance with the present invention. Fig. 2 is an enlarged horizontal sectional view on the line 2—2 of Fig. 1. Fig. 3 is a similar view on the line 3—3 of Fig. 1. Fig. 4 is a view in elevation of one of the cleaners. 45 Fig. 5 is a perspective view of the same. Fig. 6 is a fragmentary side elevation of a spark plug showing a modified form of the invention. Fig. 7 is a similar view showing a further modified construction.

50 Referring now to the drawing in detail, 1 designates a spark plug of any suitable construction embodying a power electrode 2 and a ground electrode 3. In the present instance, the terminals of the electrodes at the 55 spark gap are bent into U-form as at 4 and the legs of these U-shaped terminals lie in

parallelism with one another and are spaced apart to form the spark gap. Slidably mounted within each U-shaped terminal is a cleaner 5 comprising a block of suitable material substantially triangular in cross section and having the apex thereof formed with a longitudinal groove 6 that receives one leg of the terminal, and the base thereof formed with a relatively wide groove 7 that 60 receives the other leg of the terminal. Also formed in the block at the apex thereof is a transverse groove 8 intersecting the longitudinal groove 6 and coöperating therewith to divide the apex of the block into a plurality of scrapers that serve to scrape any carbon or other material from the adjacent leg of the electrode. The groove 7 in the base of each block is relatively wide, as compared with the diameter or thickness of the 65 adjacent leg of the electrode so that the block may swing laterally in its vertical sliding movement upon the electrode. The cleaners are mounted upon the electrodes so as to move freely thereon both longitudinally and 70 angularly, such movements being brought about automatically by the vibration or jar to which the engine is subjected when in operation. It is to be understood that the cleaners may be moved automatically in any 75 manner, advantage being taken of the force rendered by compression, explosion and the 80 influx of the gases, and such force may be supplementary to the result from shock, jar or vibration.

90 In accordance with my present invention, I secure to the inner end of the shell of the spark plug, a spring arm 9 disposed in the path of movement of the cleaner 5 on the ground electrode and this arm receives the 95 impact of the cleaner in the movement thereof toward the inner end of the shell and is flexed or bent by such impact so that the same may react and restore the cleaners to normal position, thereby preventing sticking 100 of the cleaners in the continued use of the plug. The arm 9 also acts to prevent short circuiting of the electrodes.

105 In the preferred form of the invention, I have shown the central members of the respective electrodes as inclined downwardly toward the axis of the plug, while in Fig. 6, the central members of the respective electrodes are shown as straight and in Fig. 7 as looped. It is to be understood, however, 110 that the central members of the electrodes may be shaped in any desired manner.

While I have herein shown and described certain preferred forms of my invention by way of illustration, I wish it to be understood that I do not limit or confine myself to the precise details of construction herein described and delineated, as modification and variation may be made within the scope of the claim without departing from the spirit of the invention.

10 I claim:

A spark plug having a power electrode and a ground electrode, the terminals of said electrodes being bent into U-forms, a metallic cleaner consisting of a triangular body formed upon its apex with a transverse groove adapted to fit around in slidable and swivelable relation the bent terminal of each electrode, said triangular body being formed upon its base side with an arcuate surface

adapted to contact the main stem of the single electrode, and a pair of stop flanges formed integrally upon the opposite edges of said triangular body between the limits of which said body may move, said triangular body being also formed with a transverse groove intersecting the first named groove to divide the apex of said body into a plurality of scrapers, and a spring arm secured upon the spark plug and projecting in the path of movement of one of said triangular bodies so as to be tensioned to cause a rebound of the body.

In testimony whereof I affix my signature in presence of two witnesses.

OTTO RICKMEYER.
